UNITED STATES PATENT OFFICE.

WALDO SHELDON, OF GREENWICH, CONNECTICUT.

WELL DRILLING.

Application filed May 9, 1924. Serial No. 711,982.

This invention relates to well drilling apparatus of the "rotary" type.

The objects of the invention are to provide an apparatus in which all the advantages of the rotary are retained with the added features of a power feed for positively advancing or withdrawing the drill stem, all embodied in a strong, simple, compact structure, free of undesirable complications and adapted to be substituted in place of an ordinary rotary.

These objects and others are attained in this invention by various novel features of construction, combinations and relations of parts as set forth in the following specification.

The drawings accompanying and forming part of this specification illustrate the invention embodied in one practical form, but it should be understood that the structure may be modified and changed in various respects without departure from the broad spirit and scope of the invention as herein-after defined and claimed.

Figure 1 is a part sectional side elevation of the apparatus.

Figure 2 is a top plan and part sectional view, the sectional portion being taken on substantially the plane of line 2—2 of Figure 1.

Figure 3 is a cross sectional view on substantially the plane of line 3—3 of Figure 1.

The rotary table 5 is of special construction in that it is made with an elongated dependent sleeve extension 6 having an elongated bearing in the dependent tubular extension 7 of the base 8 of the rotary. This base is secured on a bed plate 9 supported directly on two I-beams 10 spaced far enough apart for the entire apparatus to be withdrawn through the seat 11 provided in the bed plate.

At the top the rotary table is supported on a ball or taper roller bearing 12 and at the bottom a similar bearing 13 is shown interposed between the lower end of the bearing sleeve 7 and an outstanding annular thrust shoulder 14 on the lower end of the tubular extension of the rotary. The rotary is thus made capable of carrying vertical loads in either direction with a minimum of friction and the elongated bearing sleeve guides the table and steadies it against any tendencies to wobbling or gyratory movement.

A tubular drill stem engaging member 15 is slidingly keyed at 16 in the bore of the rotary so as to rotate therewith, but be free for vertical lifting or lowering movements. This member carries suitable means for gripping the drill stem, such as the adapter 17, supporting bushing 18 engaging vertical shoulders in the stem and the swing clamps 19 for engagement with transverse shoulders on the stem.

The drill stem driving sleeve is raised and lowered in the present disclosure by a stationary power cylinder of annular construction having an annular piston connected in relatively rotatable fashion with the drill stem sleeve.

The outer and inner cylindrical walls defining the annular power cylinder are designated 20 and 21 respectively, connected at the lower end by an annular cylinder head 22, the outer wall being secured by a flange extension 23 to the lower end of the table base and the inner wall extending up inside the base far enough to guide and cover the inside of the annular piston rod 24. The head of the piston 25 is attached to the lower end of this annular piston rod and suitable packing rings 26, 27, which may be of ordinary annular form are shown provided about the head of the piston and about the inside of the annular piston rod so as to prevent leakage past the piston. To provide a power applying connection between the relatively stationary piston rod and the rotating drill driving sleeve, the piston rod is shown equipped with longitudinally spaced upwardly and downwardly facing thrust shoulders 28, 29 opposed to overstanding and underlying shoulders 30, 31 carried by the drive sleeve, with interposed ball or roller bearings 32, 33 to reduce friction at these points.

Suitable connections are provided to the cylinder above and below the annular piston such as indicated at 34, 35 and by means of appropriate valve mechanism, the water or other fluid under pressure is admitted and exhausted in a manner to impart any desired lifting or lowering movement to the piston and through the rotative connection to the drive sleeve and the drill stem engaged thereby. It is thus possible to apply any desired lifting or lowering force to the drill stem and to operate the drill stem at varying pressures in accordance with condi-

tions encountered. In Figure 1 a skirt portion 36 is shown dependent from the inwardly extending flange 30, which projects down inside the piston, in opposition to the 5 upwardly projecting inner wall 21 of the cylinder, covering the upper end of the piston and forming a seat for the adapter 17.

The power mechanism is concentric with the rotary and this with the elongated construction of the bearing sleeve and the power cylinder extension provides a self-centered, balanced and well guided structure, running true at all times and capable of operating rapidly and accurately at all depths.

15 The construction of the entire apparatus as a concentric unit makes it possible to handle the complete table and power cylinder mechanism as one part and to lift the device as an entirety up between the supporting beams and out of its seat in the bed plate. This makes it possible to readily interchange one unit for another while repairs are being made and thus keep the drilling continuous or practically so.

25 What is claimed is:

1. In well drilling apparatus, a rotary table having a dependent sleeve extension, an elongated tubular bearing for said sleeve, an annular cylinder supported by said bearing in stationary relation below the rotary table and an annular piston operating in said cylinder having an annular piston rod projecting upwardly within the dependent sleeve extension of the rotary table and a 35 sleeve shiftably engaged by said annular piston rod, said engaged sleeve being slidably keyed in the table sleeve and provided with means of connection with a drill stem.

2. In well drilling, a rotary table, a drill 40 stem driving sleeve slidably keyed in said table and provided with drill stem holding means, a stationary annular cylinder supported below said rotary table and a non-rotating annular piston operating in said cylinder provided with an upwardly projecting annular piston rod having a relatively rotatable connection with the drill stem driving sleeve.

3. In well drilling, a rotary table, a drill 45 stem driving sleeve slidably keyed in said table, a concentric annular fixed cylinder supported below the table independently thereof, an annular piston in said cylinder having an annular piston rod extending up 55 into the drive sleeve and relatively rotatable pressure applying connections between the annular piston rod and drive sleeve.

4. In well drilling, a rotary table, a drill 60 stem driving sleeve slidably keyed in said table, a concentric annular fixed cylinder supported below the table independently thereof, an annular piston in said cylinder having an annular piston rod extending up into the drive sleeve and relatively rotatable pressure applying connections between the annu-

lar piston rod and drive sleeve, including thrust shoulders at the upper and lower ends of the drive sleeve and opposed correspondingly spaced thrust shoulders on the annular piston rod.

5. In well drilling, a rotary table, a drive sleeve slidably keyed in said table, a stationary annular cylinder supported below the table having an inner wall extending up within the drive sleeve, an annular piston in the cylinder having an annular piston rod projecting up over the upward extension of the annular cylinder and thrust bearing connections between the annular piston rod and drive sleeve.

6. In well drilling, a rotary table having a dependent sleeve, a base for the table having an elongated bearing for said sleeve, a thrust bearing between the lower end of the table sleeve and the elongated bearing therefor, a drive sleeve slidably keyed in the table, upwardly and downwardly faced thrust shoulders on said drive sleeve, an annular piston rod having thrust shoulders opposed to the thrust shoulders of the drive sleeve, an annular piston on the lower end of said rod and an annular cylinder receiving the piston and piston rod.

7. In well drilling, a rotary table having a dependent sleeve, a base for the table having an elongated bearing for said sleeve, a thrust bearing between the lower end of the table sleeve and the elongated bearing therefor, a drive sleeve slidably keyed in the table, upwardly and downwardly faced thrust shoulders on said drive sleeve, an annular piston rod having thrust shoulders opposed to the thrust shoulders of the drive sleeve, an annular piston on the lower end of said rod and an annular cylinder receiving the piston and piston rod, the annular cylinder being supported in dependent relation from the bearing for the table sleeve and having the inside wall of the same extended up inside the annular piston rod.

8. In well drilling, a rotary table, a concentrically disposed annular power cylinder supported in stationary relation below said rotary table, an annular piston within the same having an annular piston rod projecting upwardly within the rotary table, a drill stem driving sleeve between the annular piston rod and rotary table and slidably keyed to the table and relatively rotative connections between the annular piston rod and said drill stem driving sleeve.

9. In well drilling, a pair of spaced supporting beams, a bed plate mounted thereon provided with a seat between the beams, a table base supported in said seat and having a dependent tubular extension lying between the beams, a rotary journaled on said base and having a dependent tubular extension journaled in the bearing sleeve, an annular power cylinder carried by said de-

pendent bearing sleeve, an annular piston in the cylinder having an annular piston rod, drill stem engaging means and relatively rotative connections between the annular piston rod and drill stem engaging means.

10. In well drilling, spaced supports and rotary well drilling mechanism mounted on said supports and withdrawable from between the same as a unit, comprising a rotary, a base for the same, an annular power cylinder carried by and dependent from said base, a piston in the cylinder having an upwardly projecting annular piston rod, a drill stem driving sleeve slidably keyed in 15 the rotary above said power cylinder and a relatively rotative connection between the annular piston rod and drill stem engaging sleeve.

11. In well drilling, a rotary table having a dependent sleeve, a base for the table having a dependent tubular bearing for said sleeve, a drill stem driving sleeve slidably keyed in the table sleeve, a dependent annular cylinder carried by the bearing for 25 the table sleeve, a piston in said cylinder having an annular piston rod and relatively rotative power applying thrust connections between the annular piston and drive sleeve.

12. In well drilling, a base having a dependent elongated bearing, a rotary table having a dependent sleeve extension journaled in said elongated bearing, reversely operating thrust bearings at the upper and lower ends of said sleeve for carrying both 35 upward and downward thrust loads on the table, a drill stem driving sleeve slidably keyed in the sleeve of said table, drill stem engaging means removably seated in the upper end of said driving sleeve, reversely operating thrust bearings engaged with said 40 driving sleeve and power mechanism having a relatively rotatable engagement with said last mentioned thrust bearings for positively raising and lowering said driving sleeve 45 within the table sleeve.

13. In well drilling, a base having a dependent elongated bearing, a rotary table having a dependent sleeve extension journaled in said elongated bearing, reversely operating thrust bearings at the upper and lower ends of said sleeve for carrying both upward and downward thrust loads on the table, a drill stem driving sleeve slidably keyed in the sleeve of said table, drill stem 55 engaging means removably seated in the upper end of said driving sleeve, reversely operating thrust bearings engaged with said driving sleeve and power mechanism having a relatively rotatable engagement with said 60 last mentioned thrust bearings for positively raising and lowering said driving sleeve within the table sleeve, said last mentioned thrust bearings being disposed at the upper and lower ends of the driving sleeve and the 65 power mechanism including a cylinder con-

centric to the driving sleeve and having an annular piston rod with spaced reversely faced thrust shoulders engaging the thrust bearings of the driving sleeve.

14. In well drilling, a base having an elongated dependent externally ribbed bearing sleeve, a rotary table having a dependent sleeve journaled in said bearing sleeve, reversely facing thrust bearings for said table at the upper and lower ends of said bearing sleeve, a drive sleeve slidably keyed in said table sleeve, a concentrically arranged cylinder having an annular piston rod with spaced reversely faced thrust shoulders connected by external ribs and disposed within the drive sleeve, reversely faced thrust bearings interposed between the thrust shoulders of the piston rod and carried by the end portions of said drive sleeve and drill stem engaging means carried by said drive sleeve. 70 75 80 85

15. In well drilling, supporting means having a seat, and a power feed rotary insertible into and withdrawable from said seat as a combined unit, comprising a base to rest on said supporting means and having a bearing sleeve extending down into said seat, a rotary table having an elongated dependent sleeve journaled in said bearing sleeve, a power cylinder supported from said bearing sleeve and having an annular piston rod 90 extending up into the sleeve of the table, a drill stem driving sleeve slidably keyed in the sleeve of the table, spaced thrust bearing connections between the piston rod and the driving sleeve and drill stem engaging 95 means carried by said driving sleeve. 100

16. In well drilling, a base having an elongated dependent bearing sleeve, a rotary table having an elongated dependent sleeve journaled in said bearing sleeve, a drill stem 105 driving sleeve slidably keyed in the table sleeve and lowerable thereinto substantially flush with the table top, drill stem engaging means seated in the upper end of said driving sleeve and a power cylinder supported 110 below the table provided with a piston having a relatively rotatable power applying connection with the driving sleeve at a point within the dependent sleeve of the table.

17. In well drilling, a rotary table, a drill 115 stem driving sleeve slidably keyed in said table, a power cylinder, a piston in said cylinder having an annular piston rod projecting up within the driving sleeve, said driving sleeve having an inwardly projecting shoulder overstanding the upper end of said annular piston rod and thrust transmitting connections between the piston rod and sleeve beneath said shoulder. 120

18. In well drilling, a rotary table, a drill 125 stem driving sleeve slidably keyed in said table, a power cylinder, a piston in said cylinder having an annular piston rod projecting up within the driving sleeve, said driving sleeve having an inwardly projecting 130

shoulder overstanding the upper end of said annular piston rod, thrust transmitting connections between the piston rod and sleeve beneath said shoulder and a skirt portion 5 dependent from said inwardly projecting shoulder and extending down inside the upper end of the annular piston rod.

19. In well drilling, a rotary table, a drill stem driving sleeve slidably keyed in said 10 table, a power cylinder, a piston in said cylinder having an annular piston rod projecting up within the driving sleeve, said driving sleeve having an inwardly projecting shoulder overstanding the upper end of said 15 annular piston rod, thrust transmitting connections between the piston rod and sleeve beneath said shoulder, a skirt portion dependent from said inwardly projecting shoulder and extending down inside the upper 20 end of the annular piston rod and an adapter seated in said dependent skirt portion of the driving sleeve.

20. In well drilling, a rotary table, a drill stem driving sleeve slidably keyed in said 25 table, a power cylinder, a piston in said cylinder having an annular piston rod projecting up within the driving sleeve, said driving sleeve having an inwardly projecting shoulder overstanding the upper end of said 30 annular piston rod and thrust transmitting connections between the piston rod and sleeve beneath said shoulder, including an inwardly extending shoulder at the lower end of the driving sleeve, said piston rod having thrust 35 shoulders opposed to said upper and lower sleeve shoulders.

21. In well drilling, a rotary table, a drill stem driving sleeve slidably keyed in said 40 table, a power cylinder, a piston in said cylinder having an annular piston rod projecting up within the driving sleeve, said driving sleeve having an inwardly projecting shoulder overstanding the upper end of said 45 annular piston rod, thrust transmitting connections between the piston rod and sleeve beneath said shoulder and a skirt portion

dependent from said inwardly projecting shoulder and extending down inside the upper end of the annular piston rod, the power cylinder having an inner wall projecting upwardly within the piston rod in opposition to said dependent skirt portion of the driving sleeve. 50

22. In well drilling, a rotary table, a drill stem driving sleeve slidably keyed in said 55 table, adjustable drill stem driving means carried by said sleeve, a power cylinder having an inner annular wall extending up inside the driving sleeve, an annular piston in said cylinder having an annular piston 60 rod extending up outside said inner cylinder wall and thrust transmitting connections between said piston rod and driving sleeve.

23. In well drilling, a rotary table, a drill stem driving sleeve slidably keyed in said 65 table, a power cylinder having an inner annular wall extending up inside the driving sleeve, an annular piston in said cylinder having an annular piston rod extending up outside said inner cylinder wall and thrust 70 transmitting connections between said piston rod and driving sleeve, including reversely facing thrust bearings at the upper and lower ends of the driving sleeve, the drive sleeve carrying a dependent portion 75 at its upper end, inside the upper end of the annular piston rod and opposed to the upper end of the inner cylinder wall.

24. In well drilling apparatus, a rotary table, a concentrically mounted drill stem 80 driving sleeve, a power cylinder, a piston operating in said cylinder and having a relatively rotatable connection with said sleeve for raising and lowering the same in the rotary table and means for releasably keying 85 said drive sleeve in the table whereby said drive sleeve may be caused to rotate with the table or remain at rest in respect thereto.

In witness whereof, I have hereunto set my hand this 2nd day of May, 1924.

WALDO SHELDON.
